[57] CLAIM

The ornamental design for a lug for a bicycle frame for connecting seat tube to top tube, as shown.

DESCRIPTION

FIG. 1 is a perspective view of a lug for a bicycle frame for connecting seat tube to top tube showing our new design;

FIG. 2 is a top plan view thereof;

FIG. 3 is a right side elevational view thereof;

FIG. 4 is a left side elevational view thereof;

FIG. 5 is a bottom plan view thereof;

FIG. 6 is a front elevational view thereof; and,

FIG. 7 is a rear elevational view thereof.

FIG. 1

FIG. 4

FIG. 2

FIG. 3

FIG. 5

FIG. 6

FIG. 7

UNITED STATES PATENT AND TRADEMARK OFFICE
CERTIFICATE OF CORRECTION

PATENT NO. : Des. 337,974

DATED : August 3, 1993

INVENTOR(S) : Marc Muller; Christopher Fiorini; Mark Norris
and Clifford F. Mueller

It is certified that error appears in the above-identified patent and that said Letters Patent is hereby corrected as shown below:

Title page, item [75]

Please correct the list of inventors, as follows:

Marc Muller and Christopher Fiorini, both of Waterford,
Wisconsin; Mark Norris, West Vancouver, British
Columbia, Canada; and Clifford F. Mueller, Palatine,
Illinois.

Signed and Sealed this
First Day of February, 1994
